UNITED STATES PATENT OFFICE.

ELLA KRUPICKA, OF NEW YORK, N. Y., ASSIGNOR TO SUSQUEHANNA SILK MILLS, OF NEW YORK, N. Y., A CORPORATION OF NEW YORK.

DESIGN FOR A SILK FABRIC.

53,595.

Specification for Design.

Patented July 15, 1919.

Application filed April 5, 1919. Serial No. 287,842. Term of patent 3½ years.

To all whom it may concern:

Be it known that I, ELLA KRUPICKA, a citizen of the United States of America, residing at the borough of Manhattan, in the county of New York, city and State of New York, have invented a certain new, original, and ornamental Design for a Silk Fabric, of which the following is a specification, reference being had to the accompanying drawing, forming a part thereof.

The figure is a plan view of a piece of silk fabric, showing my new design.

I claim:

The ornamental design for a silk fabric as shown.

In testimony whereof I hereunto affix my signature.

ELLA KRUPICKA.
